TWO-FLUID REFRIGERATION SYSTEM

Lyman F. Whitney, Boston, Mass., assignor, by
mesne assignments, to Stator Company, a cor-
poration of Massachusetts

Application October 4, 1949, Serial No. 119,489

9 Claims. (Cl. 62—126)

1

This invention relates to refrigeration apparatus of the type shown in United States Patents Nos. 1,761,551 and 2,180,447, and more particularly to an improved evaporator for such systems.

Conventional refrigerating apparatus embodies an evaporator disposed in heat transfer relation to the cooling and/or freezing compartment and which contains a refrigerant, the vapors of which are pumped from the evaporator, condensed, and the condensate then returned to the evaporator. Non-aqueous refrigerants having high vapor pressures evaporate freely throughout the liquid mass by boiling, agitating the liquid mass and bringing it in contact with vapor. Thus any portion of the liquid mass located so as to receive heat from the space to be refrigerated can absorb that heat continuously by ebullition. The same is not true of aqueous and other refrigerants having low volatility, for at the low temperatures required by present-day refrigeration their vapor pressures are so low that in the absence of dissolved gases no bubbles will ordinarily form below the free surface of the liquid unless the latter becomes substantially superheated. Thus the mass is not agitated by boiling, and the free surface gets all the cooling, which is not readily communicated elsewhere due to the low heat-transmissivity of quiescent liquids. Hence, the coldest portion of the evaporator is that adjacent to the line of contact between liquid and vapor, which affords a limited area for cooling an adequate refrigeration space. Enough copper, aluminum or other good heat-conductor to distribute the cooling effect would be bulky, expensive and generally impractical.

Although the trouble could theoretically be remedied by introducing the condensed refrigerant at a point close to the top of the evaporator so as to trickle down the evaporator walls in a thin film, as a practical matter this method encounters certain difficulties including a need for precise levelling to spread the flow to all sides of the evaporator. Relatively slight mislevelling tends to flood one portion of the walls and leave the rest dry.

The difficulty is aggravated by the need of a dissolved volatile antifreeze. An ideal substance for this purpose would vaporize with the water in unchanged proportions (azeotropic solution), but such solutions are not very common at any specified temperature and pressure, and the antifreeze must meet so many other requirements (such as thermal stability; non-reactivity with water, iron or mercury; non-emulsifying tendency, etc.) that only a rough approximation to the

2

desired volatility has yet been achieved. Too volatile a substance would cause prohibitive difficulty by failure to condense fully with the water vapor, blocking the condenser with accumulated vapor and causing the pressure to rise too high for the ejector to pump against it. This leaves, as the lesser evil, a choice of antifreeze which vaporizes less readily than the water and accumulates at the evaporating surface, lowering the vapor pressure.

The principal objects of the present invention are to overcome the aforementioned difficulties and to provide a system effective to insure adequate evaporation of refrigerant with little superheating, and to distribute the cooling effect throughout an extensive refrigeration space and control its temperature, without requiring relatively costly, heavy or bulky apparatus.

A more specific object is to provide an efficient heat conveyor to absorb heat from a substantial frozen food space and deliver it at a higher gravitational level to the restricted region where the aqueous refrigerant can absorb said heat by evaporation.

A further object is to provide an improved purging system which is designed so as to insure continuous removal of extraneous gases from the system without danger of becoming sludge-bound.

Further objects relate to various features of construction and will be apparent from a consideration of the following disclosure.

In accordance with the present invention I provide a refrigerating apparatus or system which includes a compartment having therein an enclosed evaporator or cooler containing a normally liquid primary refrigerant, such as water containing a suitable antifreeze agent, spaced below the upper wall of the evaporator, so as to provide a liquid-vapor interface. Disposed within the evaporator is a portion of an enclosure adjacent to the liquid-vapor interface so as to transfer heat thereto, and another portion of the enclosure is disposed outside the evaporator and at a level below the liquid-vapor interface but in heat transfer relation to the storage compartment so as to receive heat therefrom. This enclosure contains a fluid or secondary refrigerant having a vapor pressure greater than water or the primary refrigerant in the evaporator and is normally under such pressure as will cause it to circulate through the enclosure in response to a temperature differential between the liquid-vapor interface and the interior of the compartment by reason of the secondary fluid receiving heat from the storage compartment which results in vaporization, the

vapors being conducted to the part of the enclosure at or adjacent to the liquid-vapor interface where they give up their latent heat of vaporization by condensation, the condensate then returning by gravity to the lower part of the enclosure. The secondary refrigerant preferably consists of a halogenated paraffin such as a chlorofluoro derivative of methane or ethane sold under the trade name Freon.

The enclosure containing the secondary fluid or refrigerant may be in the form of a housing in telescoping relation to the evaporator and in heat-transfer relation to the main compartment; or it may be in the form of a coil, a conduit or other enclosure having a part in heat-transfer relation to the liquid-vapor interface and another part in heat-transfer relation to the main compartment and at a level below the liquid-vapor interface, as shown in the accompanying drawings which illustrate different embodiments of the invention as applied to a modern domestic refrigerator.

In the drawings:

Fig. 12 is an elevation of my improved purger; and

Figs. 13 and 14 are fragmentary elevations illustrating modified purger connections.

Referring to Fig. 1, the refrigerating system shown therein comprises a boiler 1 having a suitable heater such as a gas burner assembly 2 and a draft-inducing flue 3, only a portion of which is shown. Mercury vapor passes from the boiler 1 through a riser 5 to the branches 5^a and 5^b which are connected, respectively, to the interconnected first and second stage aspirators 6^a and 6^b of a multiple stage ejector. The first stage aspirator 6^a is connected by a vapor duct 8 to my improved cooler or evaporator 11 (hereinafter more fully described) which contains a body of aqueous refrigerant containing a suitable antifreeze agent. Vapor is drawn through the duct 8 to the mixing chamber of the first stage aspirator and the mixed propellant mercury vapor and the refrigerant vapors are passed through the aspirator where the refrigerant is compressed and the mercury is condensed.

The condensed mercury flows from the first stage aspirator into a drain 14 while the compressed vapor passes through a duct 15 to the second stage aspirator 6^b into which a second stream of mercury vapor flows from the line 5^b, this latter propellant stream causing a further compression of the refrigerant vapor in the sec-

ond stage aspirator. Drains 27 and 27^a receive the condensed mercury from the second stage aspirator and the two drains 27 and 27^a join the drain 14 at 28 and 28^a, respectively, the drain 14 being connected to an inclined drain line 31 which is normally filled with mercury. The compressed refrigerant passes upwardly from the second stage aspirator through duct 29 to the refrigerant condenser 30. The condenser 30 may be of any suitable form and is here shown as being disposed within a water tank or reservoir T, as in Patent No. 2,174,302, granted September 26, 1939, to which reference may be had for a more detailed description of the system.

A chamber or drum 32 is preferably located at the end of the condenser 30 remote from the inlet of the pipe 29, and one end of a pipe 39 communicates with the chamber 32 so as to receive noncondensable gases therefrom. The lower portion of this chamber is connected with a drain or refrigerant return pipe 34 through which the condensed refrigerant passes on its way back to the cooler 11.

The lower end of return pipe 34 is connected with the upper end of the inclined drain line 31 and also with a vertically extending double bend, having legs 40 and 41 through which condensed refrigerant standing in line 34 pushes through the mercury at its junction with leg 40 and pipe 34, and thus makes its way back to the cooler 11. The junction 43 of the lower end of the drains 31 and 14 is connected with an upwardly inclined spill-over line 42 which is connected with the line 39 at 60, which connection determines the normal mercury level L of the system.

The lower end of the leg 41 is connected to the intermediate portion of a vertical capillary tube 45, the upper and lower ends of which are respectively connected with inlet and outlet openings at the top and bottom of the cooler 11, as hereinafter more fully explained. The parts 41 and 45 provide a vapor lift, as more fully explained in the copending application of Eastman A. Weaver, Serial No. 60,881, filed November 19, 1948.

The lower end of cooler 11 is provided with a sludge drain 46 connected to the central part of a drum 48, the upper end of which is connected by a line 50 with a mercury return pipe and boiler feed 52, and the lower end of the drum is connected by a line 54 with the return line 52 at a level slightly higher than the junction of drain 46 and drum 48. The upper end of this return line 52 is hooked so as to connect in at the top of vapor duct 8, and its lower end is connected to the inlet of boiler 1. With this construction and arrangement of parts, mercury and mercury sludge (an emulsion of mercury in the aqueous refrigerant) accumulating in the lower part of the cooler 11 flow through drain 46 into drum 48 where they are subjected to the action of the low pressure in duct 8. Hence the emulsion or sludge is broken up by evaporation of the aqueous component and the mercury is returned to the boiler through line 52.

As above noted, and as shown more clearly in Fig. 12, the spill-over line 42 and lower end of line 39 are connected at 60 so as to provide a purger comprising a mercury pump in which drops or slugs of mercury run down a capillary tube 62, trapping noncondensable gases drawn from chamber 32 and compressing them to more than atmospheric pressure. The lower end of tube 62 is connected with an inclined fitting or pipe line 64, the upper end of which is provided

with a vent cap 66 open to the atmosphere and the lower end of which is connected to a return branch 68 which in turn is connected with the return line 52. With this construction and arrangement the parts 62, 64 and 68 provide a trap for the mercury which permits the entrapped gases carried down and compressed by the mercury to rise in the line 64 and escape through vent cap 66, while the mercury returns through lines 68 and 52 to the boiler 1.

The parts 62, 64, etc. are disposed in relatively close proximity to the riser 5 and are enclosed by suitable insulating material within the confines of broken line A (Fig. 1) so that they are normally maintained at a temperature above 212° F., thereby preventing an accumulation of mercury sludge in any part of the purger system.

Both the aspirators 6^a and 6^b are provided with cooling jackets interconnected by the duct 10, the first stage aspirator 6^a having a cooling line or riser 71 connected with a condenser 72 within the tank T which has the usual pump-out connection 85, cold water supply line 86, and hot water discharge line 87, as in Patent No. 2,174,302. The water in tank T is thus heated by the condensation of the primary refrigerant and the cooling fluid which absorbs a major portion of the heat of condensation from the mercury vapors.

Referring to Figs. 2 to 4, the cooler 11 comprises a hollow inner housing 101 and a hollow outer housing 102, the inner housing 101 having a bottom wall consisting of a flat inner plate 104 (Fig. 4) and a corrugated outer plate 105. The plates 104 and 105 extend upwardly to form the inner and outer side walls 106 and 107 of the housing 101 (Fig. 3), and their top and end edge portions are sealed together so that the plates 104 and 105 define an enclosure which receives a secondary fluid such as Freon, it being noted that passages in both the bottom and side walls defined by the corrugations or reinforcing grooves intercommunicate with one another.

The housing 102 is generally similar to the housing 101 in that it comprises inner and outer plates 110 and 111 formed with reinforcing dimples 112 which maintain them in properly spaced relation. These plates are shaped to provide a hollow, roof-like top wall 115 and hollow depending walls 116 and 117 intercommunicating with each other. The enclosure or outer housing thus defined by the inner and outer walls 110 and 111 receives the primary aqueous refrigerant which is normally at a level below the vapor duct outlet 118 and above the junction of tube 45 with arm 41 so as to provide at all times a liquid-vapor interface. The construction and arrangement of parts are such that the outer side wall of the inner housing 101 is in direct heat transfer relation to the inner side walls of the outer housing so that vapors of the secondary fluid in the upper part of the side walls of the inner housing quickly transfer their latent heat to that portion of the inner side walls of the outer housing contiguous or adjacent to the liquid-vapor interface which, of course, has a relatively great heat-absorbing capacity. Thus, vapors of the secondary fluid transfer their latent heat to the primary refrigerant which is constantly being vaporized and ultimately the latent heat of the latter is transferred to the water in tank T along with the heat transferred from the fluid in the cooling jackets.

The telescoping housings 101 and 102 provide

a storage compartment for receiving foods or articles to be stored, and the front may be provided with the usual doors (not shown) through which access to the interior may be had. I use a vapor lift in this embodiment similar to that disclosed in the copending application of Eastman A. Weaver Serial No. 60,881, filed November 19, 1948. To this end the inner plate 110 of the housing 102 is formed with a central trough 120, the bottom wall of which inclines from rear to front, as shown in Fig. 4. The outer plate or wall 111 is formed with an inlet opening 122 adjacent to the rear of the trough and the upper or delivery end of capillary tube 45 communicates with the opening so as to deliver liquid refrigerant to the trough. The lower end of tube 45 is connected to the rear bottom wall of the outer housing adjacent to its connection with the sludge drain 46.

The lower end of the trough 120 is connected with a J-tube 125 which provides a mercury trap operative to hold back the aqueous refrigerant in the trough and at the same time permit stray particles of mercury to pass therethrough to the bottom of the outer housing and then into the drain 46. The wetted sloping top surface of wall 110 is preferably roughened as by sandblasting or otherwise formed with capillary rugosities effective to distribute refrigerant overflowing from trough 120 over the maximum area, as in my copending application Serial No. 36,932.

In operation the vapor lift carries refrigerant from both the lower part of the outer housing and the return line 34 to the trough 120 where it overflows onto the rugose surface of the wall 110 and trickles down the inner side walls where appreciable vaporization takes place. Since the inner side walls of the outer housing are in heat-transfer relation to the outer side wall of the inner housing, the latent heat of the secondary refrigerant is readily transferred to the primary refrigerant and hence the overall efficiency and capacity of the system is greatly increased.

The same basic principles are illustrated in the embodiment of Figs. 5 to 8. The general system, as shown in Fig. 5, is substantially the same as that shown in Fig. 1, the same or similar reference characters being applied to the same or corresponding parts, but in place of a single tank T there is provided a pair of tanks T-1 and T-2 interconnected by a pipe line 80 and provided with condenser jackets 81 and 82, respectively. The jacket 81 is connected with the compressed refrigerant vapor line 29^a and provides a refrigerant condenser, and the jacket 82 is connected with the cooling fluid line 71^a and provides a condenser for the cooling fluid. The purger line 39 is connected to the chamber 32^a at the end of jacket 81 remote from line 29^a, and the valve 85 for use in initially exhausting the system is connected to the chamber 32^a.

In place of the vapor lift shown in Fig. 1, I provide an inverted U-tube or double bend having legs 40 and 41, the leg 40 being connected to the mercury return line 31 and refrigerant return 34, and the leg 41 being connected to the intermediate part of sludge drain 46, the construction and arrangement of parts being such that refrigerant standing in line 34 pushes through the mercury at the junction with leg 40 to work its way back to evaporator or cooler 11^a. The lower end of drain 46 is connected to sludge drum 48, the upper end of which is connected by a line 49 to vapor duct 8 and the lower end is connected by a line 50 both to the mercury return 52 and the vent 49,

the construction and arrangement of parts being such that sludge in the drum 48 is subjected to the action of the low pressure in duct 8 so as to evaporate the aqueous component and permit the particles of mercury to coalesce and eventually work back through line 50 to the return 52.

The cooler 11^a (Figs. 6 to 8) is, in principle, similar to the cooler 11 and comprises a storage compartment C having an inner bottom wall 201 (Fig. 7) and a corrugated or grooved outer wall 202 juxtaposed to the inner wall 201, both walls extending vertically so as to provide the side walls of the compartment. The corrugations provide fluid passages 204 which are interconnected at the corners of the compartment by enlargements 205. The lower front edge of the outer wall 201 pivotally supports a pair of upwardly swinging closure members or doors 206 and the side walls of the compartment are provided with brackets 208 for anchoring the compartment in position.

The upper portions of the side walls are connected with elongate headers 210, the bottom walls of which incline from rear to front and the rear or enlarged parts of these headers are connected with a plurality of horizontally extending, closely spaced, flattened steel tubes 212. The passages 204, headers 210 and tubes 212 thus provide a continuous circuit or enclosure which contains a secondary fluid or refrigerant such as Freon.

Extending substantially the length of the compartment and surrounding the tubes 212 is the main evaporator or enclosure which is formed of two similar sections 215 and 216, each consisting of a generally frusto-conical shell having a flange 218 at its enlarged inner end by means of which the two sections are joined, as shown in Fig. 6. The lower part of the junction of the coupling flanges 218 is provided with an opening 220 which receives the duct 46 and the upper part of the section 216 is provided with a vapor outlet 222 to which the vapor duct 8^a is connected, the construction and arrangement of parts being such that the lower portions of the tubes 212 are at all times immersed in the liquid refrigerant, the normal level of which is just above the lower portions of the tubes 212. The opening 222 must not of course extend below the desired liquid level which is maintained by a part of the wall of section 216 extending up within the welded end of vapor-duct 8^a to form a lip 223 (Fig. 7), turned slightly inward to keep spray from passing into the vapor-duct 8^a. The exterior of the tubes 212 may be sandblasted or otherwise provided with capillary rugosities so that liquid refrigerant creeps over the exposed surfaces of the tubes and keeps them wet with a thin film of the aqueous refrigerant, thus greatly increasing the area from which evaporation takes place and consequently enhancing the refrigerating effect. In order to secure the initial low pressure within the primary refrigerant circuit, the section 216 is provided with a pump-out seal 224 (Fig. 6). The inner wall portion of the sections 215 and 216 provides the upper part of the rear wall of the compartment C, and a plate or partition 225, secured to the sections 215 and 216 by brackets 226, provides the lower part of the rear wall.

It will be noted from the foregoing that the sections 215 and 216 constitute an enclosed evaporator containing the primary liquid refrigerant which is maintained at a level which provides a liquid-vapor interface, and that the tubes 212

and interconnected passages 204 constitute an enclosed circuit having parts in heat transfer relation to the liquid-vapor interface. Heat received from articles within the compartment C is absorbed by the secondary refrigerant in the passages 204 with consequent evaporation and the vapors travel upwardly through the headers 210 and then into the tubes 212, at which place the vapors transfer their latent heat to the primary refrigerant, condense and run back into the passages 204.

The embodiment shown in Figs. 9 to 11 is somewhat similar to that shown in Figs. 6 to 8 and comprises a compartment C' which is defined by a generally rectangular shell or housing 301, the front and side edges of which carry hinges 302 for supporting a pair of access doors 304. Within the housing 301 is an inner U-shaped plate 305 and an outer U-shaped plate 306 formed with spaced parallel grooves 308 which extend along the bottom wall and up the side walls. The plate 306 is also formed with a pair of header grooves 309 at the bottom wall and a pair of header grooves 310 at the upper part of the side wall, the header grooves extending transversely of the parallel grooves 308 and providing in effect inlet and outlet manifolds interconnecting the passages defined by the grooves 308.

Spaced from the rear wall of the housing 301 is a partition 312 (Fig. 11) which defines a chamber for receiving an evaporator 315 which consists essentially of an elongate enclosure of irregular shape, the top wall portions sloping downwardly from the center to each end, the side wall portions being generally vertical and the bottom wall portion being zigzag to provide a pair of spaced valleys 316 and 317 at each side of the center of the enclosure, as shown more clearly in Fig. 10. The apex of the top wall portion is formed with a vapor opening 320 connected with a vapor duct 8^b and the valleys 316 and 317 are connected with ducts 321 and 322 which converge and join a duct 324 which leads to the sludge drum 48. Within the enclosure 315 is a pair of condenser coils 325 and 326 of flattened steel tubing bent back and forth to provide six tubes, each centered at the same level with its lower portion dipping into the primary refrigerant. The outer surfaces of the tubes are sandblasted or otherwise formed with capillary rugosities so that under normal operating conditions the exposed surfaces remain wet with a creeping film of refrigerant.

One end of each tube 325 and 326 is connected with a vapor inlet tube 328 which passes through the top wall of the evaporator 315 and is connected with the vapor manifold or header 310, and the opposite end of each tube 325 and 326 is connected to a condensate return or drain 330 which passes through the bottom wall of the evaporator and is connected to the condensate manifold or header 309. The grooves or passages 308, headers 309 and 310, ducts 328 and 330, and tubes 325 and 326 provide an enclosed fluid circuit which contains a secondary fluid or refrigerant such as Freon. In operation, heat absorbed from articles within the compartment C' effects vaporization of the secondary fluid which passes through the header 310, ducts 328 into the tubes 325 and 326 where the vapors give up their latent heat to the primary refrigerant with consequent condensation and return of the condensate through the duct 330 and header 309 to the passages 308.

In the embodiments shown in Figs. 1 and 5

each of the purging outlets 32 and 32^a is connected at a low point of the condenser because air is, in general, heavier than the aqueous refrigerant vapor. If, due to contained anti-freeze vapor or for other reason the refrigerant vapor is the heavier, then the connection should be at a high point remote from the vapor inlet, as shown in Figs. 13 and 14, wherein the same reference characters as used in Figs. 1 and 5 are employed to designate the same or corresponding parts. In any case the condensed refrigerant is drawn from the condenser through return 34 which is connected at or close to the lowest point of the condenser.

While I have shown and described different desirable embodiments of the invention, it is to be understood that this disclosure is for the purpose of illustration and that various changes and modifications may be made without departing from the spirit and scope of the invention as set forth in the appended claims.

I claim:

1. Refrigerating apparatus comprising a compartment having side and bottom walls formed with intercommunicating passages, inlet and outlet ducts communicating with said passages, an enclosed evaporator in said compartment in heat transfer relation to its upper part, said evaporator containing a liquid primary refrigerant spaced from its upper wall so as to provide a liquid-vapor interface, and a conduit extending through said evaporator at a level contiguous to said liquid-vapor interface, one end of said conduit being connected with the inlet duct and the other end of said conduit being connected with the outlet duct so as to provide a continuous closed circuit, said circuit containing a secondary refrigerant adapted to circulate in response to a temperature differential between said liquid-vapor interface and the interior of said compartment, thereby transferring heat from the latter to said interface.

2. Refrigerating apparatus comprising a compartment having side and bottom walls formed with intercommunicating passages, an outlet in the upper part of one of the side walls connected with said passages and an inlet in the bottom wall connected with said passages, an enclosed evaporator in the upper part of said compartment in heat transfer relation to its upper part, said evaporator containing a primary refrigerant spaced from its upper wall so as to provide a liquid-vapor interface, and a conduit extending through said evaporator at a level contiguous to said liquid-vapor interface, one end of said conduit being connected with said inlet and the other end of said conduit being connected with said outlet so as to provide a continuous closed circuit, said circuit containing a secondary refrigerant having a vapor pressure greater than that of said primary refrigerant and adapted to circulate in response to a temperature differential between said liquid-vapor interface and the interior of said compartment, thereby transferring heat from the latter to said interface.

3. Refrigerating apparatus comprising a compartment of generally rectangular shape and having hollow intercommunicating side and bottom walls, one of the side walls having an outlet and the bottom wall having an inlet, an enclosed evaporator in the upper part of said compartment in heat transfer relation to its upper part, said evaporator containing a liquid primary refrigerant spaced from its upper wall so as to

provide a liquid-vapor interface below said outlet, a conduit extending through said evaporator at a level contiguous to said liquid-vapor interface, one end of said conduit being connected with said inlet and the other end of said conduit being connected with said outlet so as to provide a continuous closed circuit, said circuit containing a secondary refrigerant adapted to circulate in response to a temperature differential between said liquid-vapor interface and the interior of said compartment, thereby transferring heat from the latter to said interface.

4. Refrigerating apparatus comprising a compartment having side and bottom walls formed with intercommunicating passages, header elements at the upper part of said side walls communicating with said passages, an enclosed evaporator in said compartment in heat transfer relation to its upper part, said evaporator containing a liquid primary refrigerant spaced from its upper wall so as to provide a liquid-vapor interface, and a plurality of conduits extending through said evaporator at a level contiguous to said liquid-vapor interface, said conduits being connected with said header elements to provide an enclosed circuit, said circuit containing a secondary refrigerant adapted to circulate in response to a temperature differential between said liquid-vapor interface and the interior of said compartment, thereby transferring heat from the latter to said interface.

5. Refrigerating apparatus comprising a compartment having side and bottom walls formed with intercommunicating passages, header elements at the upper part of said side walls communicating with said passages, an enclosed evaporator in said compartment and containing a liquid refrigerant spaced from its upper wall so as to provide a liquid-vapor interface, and a plurality of conduits connecting said header elements and extending through said evaporator at a level such that parts extend above and other parts project below said liquid-vapor interface, the outer surfaces of said conduits being formed with capillary rugosities effective to distribute liquid refrigerant over an extended area of their surfaces, said conduits, header elements and passages defining an enclosed circuit containing a fluid adapted to circulate in response to a temperature differential between said liquid-vapor interface and the interior of said compartment, thereby transferring heat from the latter to said interface.

6. Refrigerating apparatus comprising a storage compartment of generally rectangular shape and having hollow intercommunicating side and bottom walls defining an enclosure, a header extending along the upper part of each side wall and communicating with said enclosure, an enclosed evaporator in the upper part of said compartment said evaporator having a vapor outlet at its upper part and containing a primary refrigerant spaced from its upper wall so as to provide a liquid-vapor interface below said outlet, a conduit extending through said evaporator from one header to the other at a level contiguous to said liquid-vapor interface, said compartment containing a secondary refrigerant having a vapor pressure greater than that of the primary refrigerant and adapted to flow in response to a temperature differential between said liquid-vapor interface and the interior of said compartment, thereby transferring heat from the latter to said interface.

7. Refrigerating apparatus comprising a com-

partment having side and bottom walls formed with intercommunicating passages, header elements in the upper part of the side walls communicating with said passages, an enclosed evaporator in the upper part of and in heat transfer relation to said compartment and having a vapor outlet and containing a liquid primary refrigerant at a level which provides a liquid-vapor interface below said outlet, a conduit extending through said evaporator, said conduit having parts which project above and other parts which extend below said liquid-vapor interface, said conduit connecting said header elements, said compartment containing a secondary refrigerant adapted to reflux in response to a temperature differential between said liquid-vapor interface and the interior of said compartment.

8. Refrigerating apparatus comprising a storage compartment of generally rectangular shape and having hollow inter-communicating side and bottom walls, one of the side walls having an outlet and the bottom wall having an inlet, an enclosed evaporator in the upper part of said compartment in heat transfer relation to its upper part, said evaporator containing a primary refrigerant spaced from its upper wall so as to provide a liquid-vapor interface below said outlet, a conduit extending back and forth through said evaporator at a level contiguous to said liquid-vapor interface, the ends of said conduit being connected with said inlet and outlet so as to provide a continuous closed circuit, said circuit containing a secondary refrigerant having a vapor pressure greater than that of said primary refrigerant and adapted to circulate in response to a temperature differential between said liquid-vapor interface and the interior of said

compartment, thereby transferring heat from the latter to said interface.

9. Refrigerating apparatus comprising a compartment having side and bottom walls formed with intercommunicating passages, an enclosed evaporator in said compartment in heat transfer relation to its upper part, said evaporator containing a liquid primary refrigerant spaced from its upper wall so as to provide a liquid-vapor interface, and a plurality of conduits extending through said evaporator at a level contiguous to said liquid-vapor interface, said conduits being connected with said passages to provide an enclosed secondary circuit, said secondary circuit containing a secondary refrigerant adapted to circulate in response to a temperature differential between said liquid-vapor interface and the wall of said compartment, thereby transferring heat from the latter to said interface.
